POST-MIXED BLOWPIPE FOR THERMO-CHEMICALLY REMOVING SURFACES OF METAL BODIES

Roger S. Babcock, Plainfield, N. J., assignor to
Union Carbide and Carbon Corporation, a corporation of New York

Application February 13, 1943, Serial No. 475,712

8 Claims. (Cl. 158—27.4)

1

This invention relates to apparatus for conditioning the surface of metal bodies, and more particularly to blowpipe apparatus for thermochemically removing metal from a ferrous metal body, such as a billet, bloom, slab, bar or the like.

In the casting of steel ingots and during the hot rolling of steel, defects, such as scale, cracks, seams, slag inclusions and the like form on and in the surfaces of the steel bodies and cause imperfections in the finished rolled products unless removed. In order to reduce the number of rejections of finished rolled products, such surface defects are generally removed before or during the intermediate stage of the rolling. Scale is commonly removed by pickling and other defects have often been removed by mechanically cutting or chipping away the defective surface metal. Hand operated blowpipes, commonly referred to as hand deseaming blowpipes, are now also used for thermochemically removing the defective surface metal adjacent each defect by effecting the combustion of the ferrous metal with oxygen. Recently, machines employing suitable blowpipe means have come into use for thermochemically conditioning the surfaces of billets and the like. Such machines may be used for conditioning steel shapes, either when cold or while they are at a rolling temperature and are passing from one roll stand to another in a steel mill.

Heretofore, an outstanding drawback to conditioning or desurfacing ferrous metal thermochemically with oxygen was the ever present danger of flashback in the oxy-acetylene premixing apparatus. A great deal of time and effort has been expended in improving mixers, mixed gas passages and nozzles to reduce such tendency toward flashback. Post mixing the preheat oxygen and acetylene at the face of heating heads, tips and nozzles, as disclosed and claimed in the copending application of Barnes et al., Serial No. 326,880, filed March 30, 1940, for "Blowpipe apparatus" (now Patent 2,356,196, dated August 22, 1944), produces an externally-mixed flame which is inherently free from flashback tendencies.

The main objects of the present invention, therefore, are to provide: improved apparatus for conditioning the surfaces of metal bodies which utilizes postmixed preheating flames which are entirely free of the danger of flashback; a post-mixed nozzle for deseaming or cutting, that is simple and economical in its parts, and which may be readily made from available parts and easily incorporated in standard deseaming or de-

2

surfacing apparatus; a post-mixed blowpipe nozzle that is effective and efficient in operation; a nozzle for thermochemically removing ferrous metal, having means for producing post-mixed preheat flames which do not interfere with the oxidizing gas flow; and an improved method of removing metal from a ferrous metal body.

The present invention provides blowpipe or torch means for thermally conditioning or scarfing the surface of a steel body such as a bloom or slab, or for eliminating scale, and more particularly, blowpipe means suitable for use in a machine for thermochemically removing a layer of surface metal from the body, preferably while such body is at an elevated temperature. A multiple nozzle head discharging high temperature externally mixed preheating flames and a composite substantially sheet-like stream of oxidizing gas, is moved relatively along the body and is maintained in contact with the work surface thereof during such movement in order that a substantially uniform depth of metal may be removed and the gases efficiently used.

The invention also provides a hand deseaming blowpipe provided with a post-mixed blowpipe nozzle which is adapted to discharge a stream of oxidizing gas and a plurality of relatively hard post-mixed preheating flames around the oxidizing gas stream, the arrangement being such that the post-mixed preheating flames do not interfere with the operation of the oxidizing gas stream.

More particularly, according to the invention, there is provided a post-mixed blowpipe nozzle consisting of a generally tubular body having a right end face and a central oxidizing gas passage terminating in an orifice in the end face, the body also having a plurality of preheat oxygen passages arranged around the longitudinal axis of the oxidizing gas passage in substantially parallel relation thereto, and an inclined preheat acetylene passage for each preheat oxygen passage, each pair of preheat oxygen and acetylene passages terminating in a common port in the end face. The preheat oxygen and acetylene passages of each port are preferably arranged in a common radial plane extending from the longitudinal axis of the oxidizing gas passage, with the acetylene passage on that side of the oxygen passage opposite to the oxidizing gas passage, and the included angle between each preheat oxygen passage and its acetylene passage preferably of the order of 20 degrees. The inlet ends of the acetylene passages open to the annular outer wall of the body, and are supplied

with acetylene through an annular chamber within a jacket mounted on the nozzle body.

Further, according to the invention, there is provided a method of removing metal from a ferrous metal body, which comprises applying at least one stream of oxidizing gas against said body for thermochemical reaction with the metal to be removed, while also applying a concentric series of relatively hard entirely separate post-mixed preheating flames against such body around said stream, said flames being each composed of rapidly merging streams of oxygen and acetylene.

Referring to the drawings:

Fig. 1 is a view partly in side elevation and partly in vertical cross section of desurfacing apparatus exemplifying the invention;

Fig. 2 is a front elevational view of the apparatus shown in Fig. 1;

Fig. 3 is a view in side elevation of a deseaming blowpipe exemplifying the invention;

Fig. 4 is an enlarged fragmentary view arranged in vertical cross section of the forward end of the blowpipe shown in Fig. 3;

Fig. 5 is a cross-sectional view taken on line 5—5 of Fig. 4;

Fig. 6 is an end view taken on line 6—6 of Fig. 4; and

Fig. 7 is an enlarged detail view in longitudinal section of the preheat acetylene supply jacket.

The desurfacing apparatus shown in Figs. 1 and 2 comprises a conditioning head 10 which is supported in operative position adjacent the body to be conditioned by any suitable mechanism especially when the conditioning head is adapted for desurfacing a ferrous metal body, such as that shown and described in patent application of Keller et al. Serial No. 334,510, filed May 11, 1940, now Patent 2,312,418 dated March 2, 1943. Such mechanism preferably includes means for moving the desurfacing head 10 in a direction toward and away from the body prior to and after a surface removing operation, while the body is propelled longitudinally with the head 10 held in contact with the surface thereof during the surface removing operation. If desired, the body may be stationary and the head 10 may be propelled along the body. In any case, relative movement is provided between the body and the head 10 in such a direction as to remove successive portions of surface metal from the body. The head 10 is shown in position for desurfacing the bottom surface of a body which is supported and propelled in the direction of its length. The number of heads employed depends upon the width of the surface to be conditioned.

The blowpipe head 10 includes a nozzle retaining member or block 11 and a removable nozzle protecting shoe 12. The head 10 is removably attached to a carrier plate by threaded studs 13. Within the block 11 there are a plurality of similar oxidizing gas passages 14 each of which terminates in an enlarged and partly threaded recess 15 at its forward outlet end, to operatively receive the inlet end of a nozzle 16 removably secured therein by an externally threaded nozzle retaining nut 17. The inlet end of each passage 14 communicates with a chamber 18 formed in the block 11, there being a chamber 18 for each two passages 14. The inlet end of each chamber 18 is adapted to receive the threaded end or connection 19 of an oxidizing gas supply tube which in turn communicates with a suitable source of oxidizing gas. The oxidizing gas flows from each supply tube, through the distributing chamber 18,

the two oxidizing gas passages 14, and through the central oxidizing gas passages 20 of a corresponding pair of nozzles 16 secured in the block 11. The passage 20 may be formed as shown and claimed by the application of Arthur P. Scheller, Serial No. 322,965, filed March 8, 1940, for Method and apparatus for desurfacing metal, now Patent 2,353,318, dated July 18, 1944.

The outlet end of each passage 14 is formed to provide a pair of seats which coat with seating surfaces on the inlet end of the nozzle 16 to form gas-tight seals at 21 and 22. Between these seating surfaces, the inner end portion of the nozzle 16 is formed smaller in diameter to provide a preheat oxygen distributing chamber 23 for supplying the preheat oxygen to longitudinal preheat passages in the nozzle. Preheat oxygen is delivered to each of the chambers 23 by a passage 24 within the block 11, there being an inlet connection 25 for each pair of passages 24. Preheat acetylene is delivered to each of the nozzles 16 by means including an adaptor plate 26 and a pipe 27 for each blowpipe. The adaptor plate 26 is secured in place on the block 11 by screws 28, assisted by screws 29 which secure the shoe 12 to the block 11, gaskets 30 and 31 being disposed between the block 11 and plate 26, and between the plate 26 and shoe 12, respectively. The adaptor plate 26 is provided with a series of parallel acetylene passages 32, there being an acetylene passage for each nozzle 16, and an acetylene inlet connection 33 for each passage 32. Each nozzle is provided with an acetylene supply jacket 34 having an annular shoulder 36 constituting a bearing for the inner end of a compression spring 37, the outer end of which bears against a rubber ring 38 which prevents any leakage of cooling fluid from a chamber 39 in the shoe 12. The spring 37 thus functions to help hold the nozzle 16 in place with respect to the block 11, and also to hold the ring 38 in place with respect to the shoe 12. Any suitable cooling fluid, such as water, is circulated through the chamber 39 by means including a supply pipe 40. The acetylene supply pipes 27 within the cooling fluid chamber 39 are connected to the adaptor plate 26 by glands 41, so that preheat acetylene is conducted from each of the passages 32 within the plate to a jacket 34 of a nozzle 16. The internal construction of the nozzles, with respect to the preheat oxygen and acetylene passages, will be described in detail below in connection with Figs. 3 to 7.

The nozzles 16 in the blowpipe head 10 are so spaced that the sides of the individual scarfing oxygen streams from the central passages 20 merge so as to direct a substantially sheet-like stream of oxygen onto the surface of the work. A bearing surface 42 of the shoe contacts the work and is therefore subject to damage by abrasion, and to protect the shoe 12 a layer of metal, which is resistant to abrasion at high temperatures, is preferably deposited, as at 43 on the work contacting surface of the shoe 12. A portion 44 of the shoe 12 overlaps the upper corner of the block 11, so that any force or shock on the shoe is taken by the block 11, and the shoe cannot shift and damage the nozzles 16 or break or strain the screws 29.

Cooling water inlet and outlet connections are provided, one of which is shown at 45, for circulating the cooling water through a passage 46 in the block 11, as well as through the passage 39 in the shoe 12, to prevent the head from overheating in operation.

Referring to Figs. 3 to 7, inclusive, a deseaming

blowpipe B is provided, which includes a gas inlet valve body 50 having an oxygen inlet connection 51 and an acetylene inlet connection 52. The oxygen inlet connection 51 is connected to a suitable source of oxygen by means including a hose 53, while the acetylene inlet connection 52 is connected to a suitable source of acetylene through an auxiliary acetylene needle valve 54 and a hose 55. The conventional acetylene valve 56 of the blowpipe B, which normally controls the flow of preheat acetylene to a mixer within the blowpipe, is closed, or may be omitted entirely, if desired. A passage within the valve body 50 conducts the acetylene from the inlet connection 52 to an acetylene pipe 57 which is connected at one end to the body 50 and at the other to the jacket 58 surrounding the outer end portion of a nozzle body 59. An auxiliary acetylene passage is drilled through the body 50 so that the acetylene by-passes the valve 56, and is controlled by the auxiliary valve 54, thus a conventional type of blowpipe may be converted for use with the post-mixed nozzle of the present invention. Part of the oxygen delivered to the valve body 50 is conducted through a preheat oxygen passage controlled by a needle valve 60 to a pipe 61 which is connected at one end to the valve body 50 and at the other end to a head 62. A preheat oxygen passage 63 in the head 62 conducts the preheat oxygen to an annular distributing passage 64 between the head 62 and the inner end of the nozzle N. The remainder of the oxygen delivered to the blowpipe B through the inlet connection 51 is conducted through another passage in the valve body 50, which passage is provided with a cutting oxygen valve controlled by a lever 65, to an oxidizing or cutting gas pipe 66, the inner end of which is connected to the valve body 50 and the outer end of which is connected to the head 62. Thus, when the lever 65 is manipulated to open the cutting oxygen valve, oxidizing gas is delivered to the head 62 having a passage 67 therein for conducting such oxidizing gas to the inlet end 68 of a central oxidizing gas passage 69 extending axially throughout the length of the nozzle body 59.

The jacket 58 and the nozzle body 59 constitute the nozzle N which is secured in place with respect to the head 62 by a screw 70 which is sleeved over the external cylindrical surface of the body 59 and is threaded into a socket 71 of the head in a conventional manner, the inner annular end of the screw 70 engaging a shoulder 72 on the nozzle body 59 to secure the nozzle N in place with respect to the head 62. The jacket 58 is brazed or silver soldered at 73 and 74 to the nozzle body 59 which is suitably shaped to fit the jacket. The nozzle N has a flat end face 75 provided with a central oxidizing gas orifice 76 and a plurality of preheat gas ports 77 arranged in a circle about and concentric with the orifice 76. Each of the ports 77 is provided with a preheat oxygen passage 78 disposed perpendicular to the end face 75, and a preheat acetylene passage 79 disposed at an acute angle to the end face 75. The longitudinal axes of each pair of preheat oxygen and acetylene passages preferably lie in a radial plane extending from the longitudinal axis of the nozzle body 59. The body 59 of the post-mixed deseaming nozzle N is preferably made by forming a series of the inclined passages 79 between the cylindrical outer surface and the end face 75 of a conventional premixed deseaming nozzle having the central oxidizing

passage 69 and an annular series of preheat gas passages 78 in concentric relation with the central passage 69, the arrangement of the inclined passages 79 being such that each inclined passage has a port 77 at the end face 75 in common with the port of a preheat gas passage 78. The jacket 58 is then mounted on the cylindrical outer surface 80 of the nozzle body 59, to provide an annular chamber 81 for supplying all of the inclined passages 79 with preheat gas, in this case acetylene. The jacket 58 also constitutes a protective ring which prevents damage to the working end of the nozzle.

As pointed out above, the conventional premixed preheat gas passages 78 in the nozzle N are used according to the present invention as preheat oxygen passages, these passages being arranged in a circle about the longitudinal axis of the oxidizing gas passage 69, while the preheat acetylene passages 79 are arranged about the preheat oxygen passages 78, the preheat oxygen and acetylene passages terminating in the common ports 77. The oxidizing gas passage 69 in the nozzle N is of conventional shape for deseaming, having an inlet portion 82 of constant diameter which is connected to a relatively long but enlarged outlet portion 83 of constant diameter by a frusto-conical portion 84. This type of oxidizing gas passage differs from that of the desurfacing nozzle 16 wherein the oxidizing gas passage 20 is of conventional shape for desurfacing, having an inlet portion of constant diameter which is connected to a relatively short but enlarged medial portion of constant diameter by a conical portion. From the medial portion said passage communicates with the orifice 20 by a gradually tapered portion which is circular at its inner end and oblong at its outer end, the orifice being flat or "slotted," as shown in Fig. 2. Thus, a flat stream of oxidizing gas which is best suited for desurfacing is discharged by the nozzle 16, whereas a cylindrical stream of oxidizing gas which is best suited for deseaming is discharged by the nozzle N from the orifice 76.

The preheat oxygen passes through the passages 78 of the nozzle body 59 to the end face 75 at which point it is joined by the preheat acetylene that is conveyed through the pipe 57 to the jacket 58, through the annular distribution chamber 81 between the jacket and the nozzle body, and finally out through the inclined passages 79 which coincide with the preheat oxygen passages 78 at the ports 77. The included angle between each acetylene passage 79 and its preheat oxygen passage 78 is preferably limited to a maximum value of the order of 20 degrees, the angularity between the preheat passages of each port 77 being so limited to prevent the formation of a secondary envelope tending to burn within the oxidizing gas passage 69. Such an occurrence was observed when the preheat gases were reversed, that is when oxygen was supplied to the inclined passages 79 and acetylene was supplied to the perpendicular passages 78, and the angle between the preheat passages was about 60 degrees. The reason for such undesirable action is that an incomplete combustion of the gases occurs at the inner fringe of the preheat flames and the secondary envelope develops sufficient back pressure to force its way back through the oxidizing gas passage 69. By interchanging the gas connections as shown in the drawings, however, the preheat oxygen discharged by the passages 78 produces an oxygen

rich mixture at the inner fringe of the post-mixed preheat flames so that no combustible gas remains to burn inside the oxidizing gas passage 69. The value of the included angle between the preheat gas passages 78 and 79 controls the amount of deflection of the combined preheat gases and thereby contributes to the back pressure developed in the cutting oxygen passage 69. A post-mixed nozzle of the type as shown in Figs. 1 and 2, with an included angle of about 20 degrees between the outside acetylene passages and the inside oxygen passages produces no gases burning within the central oxidizing gas passage. A 20 degree angle between the preheat gas passages 78 and 79 has been found to give the best results as a compromise between a smaller angle effecting inefficient mixing of the preheat gases, keeping the flame out of the oxidizing gas passage 76 before the oxidizing gas has been turned on, and a larger angle between the preheat gas passages resulting in better mixing of the gases but in danger of the secondary envelope of the flame being bent into the oxidizing gas passage. In the secondary envelope hydrogen and carbon monoxide are formed. The presence of these combustibles in the oxidizing gas passage makes the danger of a backfire real when the oxygen is turned on in the central passage. Having fuel gas supplied through the inclined passages 79 and preheat oxygen through the passages 78 renders it less necessary for the inclined seat between the oxygen passage 68 and the distributing passage 64 to be gas tight, as a small leakage of oxygen from one passage into the other should be harmless. The resultant of the preheat gases from passages 78 and 79 is inclined inwardly toward the axis of the oxidizing gas passage a less amount than the angle between these preheat passages, inasmuch as the passage 78 is substantially normal to the work and parallel to the axis of the oxidizing gas passage 76. Under desurfacing conditions on hot and cold steel plate with the post-mixed flames produced by the nozzles of the present invention, the molten puddles produced by both types of nozzles (that is, premixed and post-mixed) with equivalent cutting oxygen passages are substantially similar. The invention also provides a relatively simple construction for post mixing the preheat gases to produce the preheat flames, without materially complicating the nozzle blocks or shoes of conventional desurfacing machines, and which entirely eliminates flashback troubles. While the invention has been shown in connection with a desurfacing head, Fig. 1, and a deseaming blowpipe, Fig. 3, it is to be understood that it may be used in connection with other blowpipe apparatus and especially blowpipe apparatus for thermochemically cutting, or conditioning the surfaces, of ferrous metal bodies.

What is claimed is:

1. A post-mixed blowpipe nozzle comprising, in combination, a body having an end face and a central oxidizing gas passage terminating in an orifice in said end face, said body also having a plurality of preheat oxygen passages arranged around the axis of said central oxidizing gas passage in spaced relation thereto, and an inclined preheat fuel gas passage for each preheat oxygen passage, each pair of preheat oxygen and fuel gas passages terminating in a common port in said end face; and means including a jacket mounted on said body providing a protective ring for said body and an annular preheat fuel

gas supply chamber for all of the preheat fuel gas passages in said body.

2. A post-mixed blowpipe nozzle as claimed by claim 1, in which the included angle between each preheat oxygen passage and its fuel gas passage does not exceed a value of the order of 20 degrees.

3. A post-mixed blowpipe nozzle which comprises an oxidizing gas passage extending longitudinally therethrough leading to a port at the flame end of the nozzle, a longitudinal preheat gas passage, a head secured to the end portion of the nozzle away from the flame end thereof and through which is a passage for connecting preheat gas to its longitudinal passage in the nozzle, a jacket secured to said nozzle adjacent the flame and forming a chamber therewith, another preheat gas passage connected to said chamber leading to a second preheat gas passage in the flame end portion of said nozzle and forming an angle of about 20° with first mentioned preheat gas passage in the nozzle, said nozzle having a gas port in the flame end thereof common to both of the preheat gas passages, the axes of said preheat gas passages intersecting adjacent the plane of the nozzle end face, and said nozzle having a plurality of other preheat gas ports symmetrically arranged with the first preheat gas port around the oxidizing gas port which is larger than said preheat gas ports, each of said preheat gas ports being supplied from the preheat gas passage connected to the head and from the preheat gas passage connected to the chamber within said jacket.

4. A blowpipe nozzle for the thermochemical removal of metal having post-mixed preheating gas passages on at least one side of an oxidizing gas passage, said preheating gas passages forming an angle between them adjacent the delivery end of the nozzle of substantially 20° and mixing their preheat gases more outside than inside said nozzle, the median of the angle between said preheat gas passages being inclined toward the axis of said oxidizing gas passage an amount less than the angle between said preheating gas passages.

5. A post-mixed nozzle having a central oxidizing gas passage, a plurality of pairs of preheat gas passages surrounding said oxidizing gas passage, one passage of each pair extending longitudinally of the nozzle, the other passage of each pair forming an angle of substantially 20 degrees with the longitudinal preheat gas passage, a jacket surrounding said nozzle adjacent the flame end thereof, a chamber between said jacket and nozzle to which said 20 degree angle gas passage is connected, the plane through the axes of each pair of preheat gas passages passing through the axis of the oxidizing gas passage, each pair of preheat gas passages forming a common port at the flame end of said nozzle.

6. A blowpipe nozzle for the thermochemical removal of metal having post-mixed preheating gas passages on at least one side of an oxidizing gas passage, said preheating gas passages forming an angle between them adjacent the delivery end of the nozzle of substantially 20° and mixing their preheat gases more outside than inside said nozzle, the median of the angle between said preheat gas passages being inclined toward the axis of said oxidizing gas passage an amount less than the angle between said preheating gas passages, said preheat gas passages having their axes lying in a plane through the axis of said oxidizing gas passage.

7. A blowpipe nozzle for the thermochemical removal of metal having post-mixed preheating

gas passages on at least one side of an oxidizing gas passage, said preheating gas passages forming an angle between them adjacent the delivery end of the nozzle of substantially 20° and mixing their preheat gases more outside than inside said nozzle, the said preheat gas passages having their axes lying in a plane through the axis of said oxidizing gas passage, at least one of said preheat gas passages having its axis substantially parallel to the axis of the oxidizing gas passage.

8. A blowpipe nozzle having a central oxidizing gas passage, a plurality of preheat gas passages surrounding said oxidizing gas passage and generally parallel thereto, a tapered end portion for reception in a tapered recess of a blowpipe head in which said nozzle is held, a jacket adjacent the flame end of said nozzle forming a gas-tight chamber between the jacket and nozzle, a preheat gas port on the flame end of said nozzle for each of said preheat gas passages, an inclined preheat gas passage within the nozzle extending between said chamber and each of said preheat gas ports, and a preheat gas passage outside the nozzle leading into said jacket chamber for supplying a preheat gas to said inclined passages.
